UNITED STATES PATENT OFFICE.

JOSEPH M. SATTERFIELD, OF BELLAIRE, OHIO.

DESIGN FOR A GRATE-FENDER.

45,649.

Specification for Design.

Patented Apr. 21, 1914.

Application filed February 16, 1914. Serial No. 819,123. Term of patent 14 years.

To all whom it may concern:

Be it known that I, JOSEPH M. SATTERFIELD, a citizen of the United States, residing at Bellaire, in the county of Belmont and State of Ohio, have invented a new, original, and ornamental Design for Grate-Fenders, of which the following is a specification, reference being had to the accompanying drawing, forming part thereof.

The figure is a perspective view of a grate fender, showing my new design.

I claim:

The ornamental design for a grate fender, as shown:

JOSEPH M. SATTERFIELD.

Witnesses:

H. E. DUNLAP,
W. F. KEEFER.
